JOURNAL BOX LID

Theodore R. Weber, Latrobe, Pa., assignor to
 American Locomotive Company, New York,
 N. Y., a corporation of New York

Application April 8, 1941, Serial No. 387,439

4 Claims. (Cl. 308—47)

This invention relates to journal box lids.

An object of the present invention is to provide a journal box lid having a cover, an energized spring, and a separate hood cooperating to hold the spring energized, the hood to this end serving at a part thereof as a cam face engaging the cam lug of the journal box.

A further object is to provide a lid of the aforementioned type in which the spring is formed of coils having looped ends forming eyes mounted on the hinge pintle for the lid and ends secured to the hood.

Other and further objects of this invention will appear from the following description, the accompanying drawing and the appended claims.

Referring to the drawing forming part of the present application, Figure 1 is a front elevation of a lid involving the present invention, the hinge pintle and journal box being shown, the latter in dot and dash lines, and the hood being broken away and shown partly in section on the line I—I of Fig 2; Fig. 2 is a section on the line II—II of Fig. 1, parts being shown in full, and the journal box being indicated fragmentally in dot and dash lines; Fig. 3 is a section on the line III—III of Fig. 2, parts being shown in full and other parts in dot and dash lines; Fig. 4 is a section on the line IV—IV of Fig. 2, parts being shown in full; and Fig. 5 is a fragmental side elevation of the lid, the box being indicated fragmentally in dot and dash lines and the hood being shown held partly open relative to the cover by an assembling and disassembling wedge.

The journal box is indicated generally by the reference numeral 1, and may be of any usual construction having the usual opening 2 at the front, and orificed cam lug 3, mounted at the top of, and preferably, as shown, formed integral with the box.

The lid, indicated generally by the reference numeral 4, comprises a cover 5, preferably made of stamped metal, having the usual strengthening ribs 6 and the peripheral flange 7. The top run of the flange 7 has formed thereon upwardly extending lugs 8 for a purpose later to be described. The cover further comprises, approximately at its center portion, a horizontal rearwardly directed depression 9 providing a seat for a spring later to be referred to. The depression at each end portion thereof has a raised seat 10 for a purpose later to be described.

The lid further comprises a spring, indicated generally by the reference numeral 11, preferably formed, as shown, as a single member but may be made of two separate springs if desired. The

spring comprises two coils 12 having their inner ends extending upwardly to form two branches 13 connected together by a U-bend 14. The coils have their outer ends also extending upwardly forming two branches 15. These outer branches extend to the lug 3, one at each side thereof, and are bent around to form loops or eyes 16. These eyes are bent from the branches proper in a rearward direction with their end portions bent in a forward direction and terminating in abutting faces 17 to the rear of, and slightly spaced from, the lugs 8 when the lid is closed upon the box.

A hinge pintle 18 is mounted in the orifice of the lug 3 and extends therefrom at each side thereof, and the eyes 16 are mounted one on each of these extended portions. The coils 12 are seated in the depression 9 between the seats 10 and are secured to the cover by a bar 19, which passes through the coils and extends therefrom at each side thereof, providing flat portions 20 which engage the seats 10 and are firmly secured thereto by rivets 21. The bar between the portions 20 engages the coils interiorly thereof and is curved transversely to conform with the interior curvature of the coils to provide a working fit for the coils. Thus the spring is anchored to the cover affording a support therefor through the office of the eyes 16 mounted upon the pintle.

The lid further comprises a hood separate from the cover and indicated generally by the reference numeral 22. The hood and cover provide a housing for the spring. The hood is formed of a front wall 23, and the spring branches 13 extend to and engage, at the U-bend 14, the inner face of this wall at approximately the center of the hood although its exact point of engagement in a vertical direction is not important.

A staple 24 embraces the U-bend, extends at its end portions through orifices in the wall 23, and these end portions are riveted over thus firmly holding the hood and spring together. The spring thus connected to the hood, and as aforesaid to the cover, provides the only means of connecting the hood and cover together. The hood at its lower portion has supported connection with the cover. This is preferably effected by resting the wall 23 at its lower portion upon the coils 12. The wall is provided with a rearwardly curved portion 25 preferably substantially following the curvature of the exterior of the coils.

The invention, as to some of its features, is not limited to an eyeless cover or hood, nor to a spring having eyes for mounting the lid upon the hinge pintle. Where a spring having eyes

is employed as aforescribed, eyes may also be provided on either the cover or hood, or both, such eyes acting mainly as auxiliary eyes to prevent loss of the lid should the spring eyes break. Of course, such hood eyes must be sufficiently large to permit movement of the hood relative to the pintle during opening and closing of the lid.

However, it is contemplated that in some cases the spring eyes may be eliminated, the spring branches 15 in such case being anchored to the cover in any suitable manner, and the cover being provided with eyes for mounting the lid upon the pintle. In such a modified structure, the hood could be either eyeless or provided with the aforesaid auxiliary eyes.

However, in all cases it is preferred to employ an eyeless hood, as hood eyes are objectionable as for instance during assembling and removal of the pintle, and furthermore an eyeless hood as shown provides simple pintle-retaining means. Obviously if the hood is provided with eyes, other pintle-retaining means must be employed. However, the construction shown in the drawing is believed to be a most practical one, and hereafter the description will be confined to the lid as therein shown.

In an eyeless hood construction the rearwardly curved portion 25 is spaced slightly from the coils 12 from its point of contact therewith downwardly and rearwardly, and its end 26 terminates somewhat short of the cover 5. This is to permit the hood at its top to be opened from the cover and to hinge about its contact with the coils.

The hood is formed with side walls 27. The spring branches 15 diverge upwardly to the eyes 16 and are then bent inwardly to dispose the eyes parallel to each other. The side walls 27 are conformed to follow the general direction of the diverging spring branches 15 and parallel eyes 16. The hood may be formed to fit the coils and branches 15 as snugly as desirable within working limits to provide minimum sidewise movement of the lower end of the hood relative to the cover.

The side walls 27, which are integral with the wall 23, extend upwardly to a top wall 28 formed integral with the side walls 27 and front wall 23. The top wall 28 extends over the top of the lug 3 in spaced relation therewith to permit opening and closing of the lid and as a preventative to the entrance of foreign matter to the interior of the hood.

The side walls 27 overlap the ends of the pintle 18 to a greater or lesser extent as desired, about one-half overlap being shown, thus preventing axial displacement movement of the pintle. As these side walls 27 are in close proximity to the eyes 16 the upper end of the hood is held against appreciable sidewise movement relative to the cover.

To assemble or remove the pintle, the hood, at its upper end, must be moved outwardly from the spring eyes 16 so that the hood sides 27 will clear the eye orifices. To accomplish this the hood is turned about the spring coils relative to the lid to a sufficient angle to clear the walls 27 from the spring eyes, that is to say, from the path of the pintle. This can be done by inserting a wedge between one side wall 27 and the cover, such a wedge being indicated at 29 in Fig. 5, where the hood is shown rotated relative to the cover a sufficient amount to clear the pintle. During this wedging action the lugs 8

engage the faces 17 as shown in Fig. 5, which holds the eyes 16, against the tension of the spring, in proper position relative to the hood and cover so that they may be assembled when desired with the pintle. Of course two wedges 29, one under each side of the hood, may be employed if desired, thus effecting direct holding of each branch 15 against movement toward the hood. With the parts as shown in Fig. 5 it will be obvious that the pintle may be withdrawn from the cam lug and eyes or inserted therethrough as desired.

The side walls 27 extend rearwardly at their upper portions to provide the parts that overlap the pintle, and as shown in Fig. 2 these extensions are cut away to provide parts 30 suitably spaced from the lugs 8.

The upper portion 31 of the wall 23 is disposed rearwardly of the lower portion and the two portions are connected by an inclined wall portion 32, this being merely for convenience of construction. The portion 31 at its central portion is depressed to provide a wall portion 33 disposed opposite the cam lug 3. The inner face 34 of this wall portion 33 provides a cam face which engages the cam lug, as clearly shown in Fig. 2.

The spring is so constructed that it will be energized when the parts are assembled as shown in Fig. 2. The spring, in conjunction with the pintle and hood, due to the hood's connection at its lower end with the cover through its engagement with the spring coils and at its upper portion 33 with the cam lug, effects a yielding pressure of the cover, when closed, upon the box. The initial opening of the cover is effected by the cover rotating about the top engaging edge of the box until the lugs 8 engage the faces 17. During further opening, the lid moves as a unit, the spring eyes rotating about the pintle, and the cam face 34 moving upward over the cam of the lug 3.

In closing the lid a somewhat reversal of the opening procedure takes place. During initial closing movement the cover swings about the spring coils until the upper portion of the cover strikes the walls 27 (which are normally more or less spaced therefrom as desired), or preferably until the lugs 8 engage the parts 30. During further closing movement the lid moves as a unit in an obvious manner. The opening and closing pressure action of the spring is similar to comparable conventional types of lids, that is to say the construction provides the jack knife blade opening and closing action. When the cover is finally closed it engages the face of the box evenly on all sides of the opening due to the flexibility of the connection between the cover and box lug, namely the hood and spring, and the flexibility of the connection between the hood and spring.

The hood may be cast or made of stamped metal. The cam face 34 should preferably be made hard to withstand the wear resulting from its movement over the cam lug under the pressure of the spring. To effect this a wear plate (not shown) may be secured in any desired way, as by welding, on the inner face of the hood at the portion 33, or the hood may be formed of tempered spring steel.

The type of spring employed, acting as it does to pull the hood into engagement with the cam lug and into connection with the cover through the coils, causes the hood to act as a lever, fulcruming about its point of engagement with the

cam lug and exerting a pressure at its lower end upon the cover holding the cover firmly against the box. The hood can therefore be disposed nearer to the cover than would be the case if the spring engaged the cam lug in accordance with usual design. As a consequence of this construction wherein the hood engages the cam lug, the entire lid is more compact and therefore lighter, and, as the hood is parallel to and close to the cover, it may be made of light stock. The lid as a whole is therefore lighter, reducing the tendency of the lid to pound on the box, which tendency increases as the weight of the lid increases. It will therefore be seen that the lid of the present invention has many desirable characteristics resulting directly from the hood-cam lug engagement and leverage features.

While there has been hereinbefore described an approved embodiment of this invention, it will be understood that many and various changes and modifications in form, arrangement of parts and details of construction thereof may be made without departing from the spirit of the invention, and that all such changes and modifications as fall within the scope of the appended claims are contemplated as a part of this invention.

The invention claimed and desired to be secured by Letters Patent is:

1. A lid for an open face journal box having an orificed cam lug mounted on the top thereof and a lid pintle mounted in said orifice and having end portions extending therebeyond at each side of said lug, said lid comprising a cover for said box open face; an eyeless hood separate from said cover and disposed at the outer face thereof with its lower end portion associated with said cover for support thereby and having at its upper end portion a front wall provided with an inner face for engaging the cam of said lug, a top wall for extending over said lug, and side walls for overlying the ends of said pintle for retaining same in place, said hood and cover cooperating to provide a spring housing; a spring within said housing affording the sole connection between said cover and said hood and between said hood and said journal box, said spring being composed of two energized spring coils disposed at the central portion of said cover; means securing said coils to said cover, each said coil at one end thereof having a branch extending upwardly and looped at its upper end to provide an eye, said eyes being adapted to be rotatably mounted, one on each of said pintle end portions, each said coil further having at its other end another branch extending upwardly to an intermediate portion of said hood; and means securing said other branches at their upper end portions to said hood, thereby, when said spring is mounted on said pintle and said cover is closed, holding said hood spring-pressed upon said cam and said cover spring-pressed upon said box.

2. A lid for an open face journal box having an orificed cam lug mounted on the top thereof and a lid pintle mounted in said orifice and having end portions extending therebeyond at each side of said lug, said lid comprising a cover for said box open face; a hood separate from said cover and disposed at the outer face thereof with its lower end portion associated with said cover for support thereby and having at its

upper end portion a front wall provided with an inner face for engaging the cam of said lug and a top wall for extending over said lug, said hood and cover cooperating to provide a spring housing; a spring within said housing affording the sole connection between said cover and said hood, said spring being composed of two energized spring coils disposed at the central portion of said cover; means securing said coils to said cover, each said coil at one end thereof having a branch extending upwardly and looped at its upper end to provide an eye, said eyes being adapted to be rotatably mounted, one on each of said pintle end portions, each said eye being open at the bottom with the face of its free end facing forward, said cover being extended upwardly in front of said end faces, said end faces serving as abutments for said cover during swinging of said lid in an opening direction, each said coil further having at its other end another branch extending upwardly to an intermediate portion of said hood; and means securing said other branches at their upper end portions to said hood, thereby, when said spring is mounted on said pintle and said cover is closed, holding said hood spring-pressed upon said cam and said cover spring-pressed upon said box.

3. A lid for an open face journal box having an orificed cam lug mounted on the top thereof and a lid pintle mounted in said orifice and having end portions extending therebeyond at each side of said lug, said lid comprising a cover for said box open face; a hood separate from said cover and disposed at the outer face thereof having at its upper end portion a front wall provided with an inner face for engaging the cam of said lug and a top wall for extending over said lug, said hood and cover cooperating to provide a spring housing; a spring within said housing affording the sole connection between said cover and said hood, said spring being composed of two horizontally aligned energized spring coils disposed at the central portion of said cover, said hood having its lower end portion supported upon and extending partly around said coils; means securing said coils to said cover, each said coil at one end thereof having a branch extending upwardly and looped at its upper end to provide an eye, said eyes being adapted to be rotatably mounted, one on each of said pintle end portions, each said coil further having at its other end another branch extending upwardly to the central portion of said hood; and means securing said other branches at their upper end portions to said hood, thereby, when said spring is mounted on said pintle and said cover is closed, holding said hood spring-pressed upon said cam and said cover spring-pressed upon said box.

4. A lid for an open face journal box having an orificed cam lug and a hinge pintle mounted in said orifice, comprising a cover means for said face; a separate hood having a cam face for spring-pressed engagement with said cam lug; energized spring means disposed between said cover means and hood, one of said means having eyes for mounting said lid on said pintle, said hood having portions for overlapping said eyes to retain said pintle, said spring means having a part secured to said cover means at substantially the central portion thereof, an upwardly extending branch exerting a force in a direction tending to move it away from said cover means, said branch and cover means having coacting

parts limiting their movement at their relative upper end portions, and another upwardly extending arm secured to said hood at an intermediate portion and exerting a force tending to pull said hood and cover means together, said hood at its lower end portion having spring-pressed engagement with one of said means and at its upper end portion being free for pivotal movement about its lower end portion away from

5 said cover means against the resistance of said spring means; and a tool temporarily disposed between said hood and cover means at a portion spaced from said hood lower end portion, said tool holding said hood upper end portion in a position outward from said cover means whereby the adjacent pintle-retaining hood portion clears the adjacent eye.

THEODORE R. WEBER.
